US00D659710S

(12) United States Design Patent
Hirt

(10) Patent No.: US D659,710 S
(45) Date of Patent: * May 15, 2012

(54) PORTION OF A DISPLAY PANEL WITH A COMPUTER GENERATED DISPLAY

D542,302 S * 5/2007 Muranaka et al. D14/495
D593,113 S * 5/2009 Ahn et al. D14/486
D613,759 S * 4/2010 Barchek et al. D14/495

(75) Inventor: Garvin Hirt, Berlin (DE)

(73) Assignee: Biomerieux (FR)

() Term: 14 Years

(21) Appl. No.: 29/376,009

(22) Filed: Sep. 30, 2010

(30) Foreign Application Priority Data

Mar. 30, 2010 (EP) 001688870-0002

(51) LOC (9) Cl. 32-00

(52) U.S. Cl. D14/494

(57) CLAIM

The ornamental design for a portion of a display panel with a computer generated display, as shown and described.

DESCRIPTION

The FIGURE is a front view of a portion of a display panel with a computer generated display showing my new design. The broken line showing of the portion of the display panel is included for the purpose of illustrating environmental structure and forms no part of the claimed design.

1 Claim, 1 Drawing Sheet
